(57) **CLAIM**

The ornamental design for a holder, as shown and described.

DESCRIPTION

FIG. 1 depicts a perspective view of a holder showing my new design.

FIG. 2 depicts a front view of the holder of FIG. 1.

FIG. 3 depicts a rear view of the holder in FIG. 1.

FIG. 4 depicts a left side view of the holder in FIG. 1.

FIG. 5 depicts a right side view of the holder in FIG. 1.

FIG. 6 depicts a top view of the holder in FIG. 1; and, FIG. 7 depicts a bottom view of the holder of FIG. 1. In the drawings, the dashed broken lines are for the purpose of illustrating portions of the article and form no part of the claimed design.

The dot-dash broken lines define the bounds of the claimed design and form no part thereof.

1 Claim, 6 Drawing Sheets
